PILOT CHUTE EJECTOR

Albert T. Stretch, Jr., Trenton, N. J., assignor to
Switlik Parachute Company, Inc., Trenton,
N. J., a corporation of New Jersey

Application February 11, 1947, Serial No. 727,905

17 Claims. (Cl. 244—148)

1

This invention relates to the usual types of parachute assemblies which include a pack that comprises a container, a parachute canopy which is suitably attached to the harness, and a pilot chute which assists in withdrawing the canopy from the container when the container is opened.

It is an object of the invention to provide a device in which the pilot chute will be positively withdrawn from the container by the operator when the ripcord is operated to release the container closure, and which is so withdrawn that it will be presented to the air stream skirt first and will withdraw the canopy of the parachute assembly from the container, peak first, and thus present it to the air stream skirt first.

It is a further object of the invention to so construct the device that it may be incorporated in parachute packs of various types.

With these and other objects in view, such as will appear as the description of the invention progresses, the invention resides in the construction and arrangement of parts illustrated in the drawing, described in the specification and recited in the claims.

In the drawings, wherein the invention is shown as applied to a back pack:

Figure 1 is an elevation of a back pack with the invention applied thereto, a portion of a body harness being shown to disclose the mounting of the ripcord handle and the pilot chute withdrawing device;

Figure 2 is a sectional view on the line 2—2 of Figure 1;

Figure 3 is an elevational view, partly in section, showing the construction of the ripcord assembly;

Figure 4 is a fragmentary elevational view showing the attachment of the pilot chute flap to the ripcord assembly;

Figure 5 is a perspective view of a pack with the invention incorporated therein, after the pack has been opened upon the release of the ripcord from the securing cones and grommets; and

Figure 6 is a diagrammatic view showing the manner in which the pilot chute is withdrawn from the pack and is released from the withdrawing flap and ripcord assembly.

Referring, now, to the construction shown in the drawings, the pack includes a back 1 and flaps 2, 3, 4 and 5. In Figure 1 the lift webs 6 and 7 are illustrated as extending from the pack and from the shroud lines in the usual manner, and a portion of one of the risers is illustrated at 8.

Referring, now, to Figure 2 of the drawings, the canopy 9 is illustrated as packed within the con-

2

tainer in the usual manner, that is to say, folded back and forth, and the shroud lines, which are attached to the skirt of the canopy at 10, lie in the usual manner against the back 1 of the container. The peak 11 of the canopy 9, with its vent, is packed adjacent the closure flaps 2, 3, 4 and 5, as illustrated in Figures 2 and 5.

The flaps are illustrated as held in their closed positions by the usual cones and grommets, the cone on the flap 2 being indicated by the reference numeral 12, the cone on the flap 4 being indicated by the reference numeral 13, and the cone on the flap 3 being indicated by the reference numeral 14.

The flap 3 is provided with grommets 15 and 16 for engagement respectively with the cones 12 and 13, while the flap 5 is provided with grommets 17 and 18 for engagement respectively with the cones 12 and 13, the flap 5 being provided with a grommet 19 for engagement with the cone 14, all of which is illustrated in Figure 2 of the drawings.

These flaps are held in their closed positions by the engagement of the grommets with the respective cones, and are locked in this position by a ripcord which later will be described, and one of the flaps is provided with a flap 20 which covers the cones and grommets and the adjacent portion of the ripcord, this flap 20 being held in place in the usual manner by detachable snap fasteners 21.

In the drawings the pilot chute is indicated by the reference character 22 and it includes the usual lines 23 and 24 for attaching it to the peak of the canopy 9 at its vent.

In order that the pilot chute may be withdrawn from the pack when the flaps are released, a fabric strip 25 is provided which is of sufficient size, both transversely and longitudinally, to permit it to be rolled with the pilot chute 22 in the manner illustrated in the drawings so that the pilot chute will be completely enclosed within the strip.

It will be observed from the drawings that the peak 26 of the pilot chute is located adjacent the central portion of the roll while the lines 23 are adjacent the outlet of the roll, and that the line 24 extends around the roll and over the top thereof to the peak of the canopy to which it is attached. The pilot chute-ejector flap 25 is arranged to extend outwardly between the flaps 2, 3, 4 and 5, and is provided with a grommet 27 which is engageable with the cone 12 below the grommet on the flap 3. This flap 25 extends beyond the cone outwardly of the pack and is attached, as at 28, to a ripcord housing 29.

This ripcord housing 29 houses the ripcord 30, which ripcord is provided with pins 31, 32 and 33 for engagement respectively with the cones 12, 14 and 13. The ripcord extends freely through the housing 29 so that it may have movement longitudinally in respect of the housing and is attached at 34 to a ripcord handle 35 in the usual manner.

Within the ripcord housing 29 a sleeve 36 is fixedly mounted adjacent the end of the housing. Through this sleeve the ripcord 30 extends and is adapted to slide, but its relative movement is limited by an abutment 37 which is rigid with the ripcord and is adapted to engage within the sleeve 36 so that any further pulling on the ripcord 30 by means of the handle will result in the movement of the ripcord and the ripcord housing as a unit.

The ripcord housing 29 is provided with a clip 38 which is rigidly attached thereto adjacent its end and the sleeve 36 is adapted to engage with a loop 39 on the riser 8 adjacent the pocket 40 in which the ripcord handle is engaged.

When the parachute assembly is completely packed the parts will be in the position illustrated in Figure 2, wherein the canopy 9, with its suspension lines and the inwardly extending portions of the lift webs 6 and 7, will be within the container, and the pilot chute 22 with the pilot chute ejector flap 25 will be rolled together and within the container on the top of the packed canopy and adjacent the peak 11 of the latter.

The flaps 2, 3, 4 and 5 will be held in their closed positions in the usual manner by the cones, grommets and ripcord pins. Moreover, the pilot chute and its ejector flap 25 will be held fixedly in the pack by the engagement of the grommet 27 with the cone 12, with the result that the ripcord housing will be releasably attached to the cone by this means.

When the ripcord is pulled, it will be drawn through the ripcord housing longitudinally to disengage the pins 31, 32 and 33, from the cones with which they cooperate. When the ripcord handle has been pulled to an extent sufficient to cause the engagement of the abutment 37 on the ripcord with the sleeve 36, the pins 31, 32 and 33 will have been completely disengaged from the cones with which they cooperate. Further pulling force applied to the ripcord handle will, because of the engagement of the abutment 37 with the sleeve 36, cause the ripcord 30 and the ripcord housing 29 to move as a unit. In this movement, the grommet 27 will be disengaged from the cone 12, with the result that if the flaps 3, 4 and 5 have not already opened, the grommets on these flaps will be disengaged from the cones and the flaps opened. Moreover, the pull exerted on the flap 2 of the container, through the grommet 27 and the cone 12, will open this flap and continued pulling on the ripcord handle will withdraw the pilot chute ejector flap 25 from the pack and this withdrawal will carry the pilot chute with it. However, because of the attachment of the line 24 to the peak of the canopy 9, the ejector flap 25 and the pilot chute will start to unroll as they are withdrawn and this unrolling will continue until the flap 25 and the pilot chute have been completely withdrawn from the pack, at which time the pilot chute 22 will be completely released from the ejector flap 25, as illustrated in Figure 6 of the drawings.

It will be observed, of course, that in this withdrawal and release of the pilot chute the

skirt of the chute will be presented to the air stream so that the pilot chute will be quickly opened. It will thereafter aid in the withdrawal of the canopy 9, peak first, so that when the canopy reaches a completely withdrawn position its skirt will be presented to the air stream and thus quickly will inflate.

It is to be understood that details and specific arrangements of the device that I have selected to illustrate my invention may be made without departing from the spirit of the invention or exceeding the scope of the claims, and I, therefore, do not wish to be limited to those details and arrangements except in so far as is made necessary by the claims.

I claim:

1. A parachute pack assembly comprising a container having a back portion and a releasable closure adapted to overlie said back portion, a parachute canopy folded upon said back portion with its peak adjacent said closure, means for attaching said canopy to a load, a pilot chute, means attaching said pilot chute to the peak of said canopy, a flexible pilot chute ejector, said pilot chute and pilot chute ejector being folded together and located upon said canopy adjacent its peak portion and located entirely within said container, said releasable closure being located over said canopy, pilot chute and pilot chute ejector, means for securing said closure and said pilot chute ejector releasably together, and means for withdrawing said pilot chute and pilot chute ejector from said pack and for freeing said pilot chute from said pilot chute ejector.

2. A parachute pack assembly comprising a container having a back portion and a releasable closure adapted to overlie said back portion, a parachute canopy folded upon said back portion with its peak adjacent said closure, means for attaching said canopy to a load, a pilot chute, means attaching said pilot chute to the peak of said canopy, a pilot chute ejector, said pilot chute and said pilot chute ejector being rolled together in convolutions and located upon said canopy adjacent its peak portion, said releasable closure being located over said canopy, pilot chute and pilot chute ejector, means for securing said closure and said pilot chute ejector releasably together, and means for withdrawing said pilot chute and said pilot chute ejector from said pack and for unrolling said pilot chute and said pilot chute ejector to free them from the latter.

3. A parachute pack assembly comprising a container having a back portion and a releasable closure adapted to overlie said back portion, a parachute canopy folded upon said back portion with its peak adjacent said closure, means for attaching said canopy to a load, a pilot chute, means attaching said pilot chute to the peak of said canopy, a pilot chute ejector, said pilot chute and pilot chute ejector being folded together and located upon said canopy adjacent its peak portion, said releasable closure being located over said canopy, pilot chute and pilot chute ejector, means for securing said closure and said pilot chute ejector releasably together, and means for withdrawing said pilot chute and pilot chute ejector from said pack and for freeing said pilot chute from said pilot chute ejector, said last mentioned means including a rip cord housing secured to said ejector.

4. A parachute pack assembly comprising a container having a back portion and a releasable closure adapted to overlie said back portion, a parachute canopy folded upon said back portion

with its peak adjacent said closure, means for attaching said canopy to a load, a pilot chute, means attaching said pilot chute to the peak of said canopy, a pilot chute ejector, said pilot chute and said pilot chute ejector being rolled together in convolutions, with said pilot chute enclosed in said ejector in convolutions and located upon said canopy adjacent its peak portion, said releasable closure being located over said canopy, pilot chute and pilot chute ejector, means for securing said closure and said pilot chute ejector releasably together, and means for withdrawing said pilot chute and said pilot chute ejector from said pack and for unrolling said pilot chute and said pilot chute ejector to free them from the latter, said last mentioned means including a ripcord housing secured to said ejector.

5. A parachute pack assembly comprising a container having a releasable portion to permit the release of a canopy, a parachute canopy packed within said container, a pilot chute attached to the peak of said canopy, a flexible ejector flap, said flap and pilot chute being rolled in convolutions, with said pilot chute enclosed in said ejector and packed entirely within said container adjacent its said releasable portion, and manually operable means for withdrawing said ejector and pilot chute from said container and for freeing said pilot chute from said ejector.

6. A parachute pack assembly comprising a container having a releasable portion to permit the release of a canopy, a parachute canopy packed within said container, a pilot chute attached to the peak of said canopy, a flexible ejector flap, said flap and pilot chute being rolled in convolutions, with said pilot chute enclosed in said ejector and packed in said container adjacent its said releasable portion, and manually operable means for withdrawing said ejector and pilot chute from said container and for freeing said pilot chute from said ejector, said means being releasably connected with said releasable portion of said container to release the same.

7. A parachute pack assembly comprising a container having a releasable portion to permit the release of a canopy, a parachute canopy packed within said container, a pilot chute attached to the peak of said canopy, a flexible ejector flap, said flap and pilot chute being folded together and packed in said container adjacent its said releasable portion, and manually operable means for withdrawing said ejector and pilot chute from said container and for freeing said pilot chute from said ejector, said means including a ripcord housing attached to said ejector and releasably attached to said container.

8. A parachute pack assembly comprising a container having a releasable portion to permit the release of a canopy, a parachute canopy packed within said container, a pilot chute attached to the peak of said canopy, a flexible ejector flap, said flap and pilot chute being folded together and packed in said container adjacent its said releasable portion, and manually operable means for withdrawing said ejector and pilot chute from said container and for freeing said pilot chute from said ejector, said means being connected with said releasable portion of said container to release the same, said means including a ripcord releasably securing said releasable portion of said container in closed position and a ripcord housing attached to said ejector and releasably attached to said container.

9. A parachute pack assembly comprising a container having a releasable portion to permit

the release of a canopy, a parachute canopy packed within said container, a pilot chute attached to the peak of said canopy, a flexible ejector flap, said flap and pilot chute being folded together and packed in said container adjacent its said releasable portion, and manually operable means for withdrawing said ejector and pilot chute from said container and for freeing said pilot chute from said ejector, said means being connected with said releasable portion of said container to release the same, said means including a ripcord releasably securing said releasable portion of said container in closed position and a ripcord housing attached to said ejector and releasably attached to said container, said ripcord having a limited relative movement within said housing, and means for limiting said movement of said ripcord within said housing.

10. A parachute pack assembly comprising a container having releasable closure flaps, means for releasably securing said flaps together, a canopy packed within said container, a pilot chute, a flexible pilot chute ejector, said pilot chute and ejector being rolled in convolutions, with said pilot chute enclosed in said ejector and packed within said container between said canopy and said flaps, and common manually operable means for releasing said flaps and withdrawing said pilot chute and said ejector from said container.

11. A parachute pack assembly comprising a container having releasable flaps, means for releasably securing said flaps together, a canopy packed within said container, a pilot chute, a pilot chute ejector, said pilot chute and said ejector being rolled together spirally and packed within said container between said canopy and said flaps, and common manually operable means for releasing said flaps and withdrawing said pilot chute and said ejector from said container.

12. A parachute pack assembly comprising a container having releasable flaps, means for releasably securing said flaps together, a canopy packed within said container, a pilot chute, a pilot chute ejector, said pilot chute and said ejector being rolled together spirally and packed within said container between said canopy and said flaps, and common manually operable means for releasing said flaps and withdrawing said pilot chute and said ejector from said container, the peak of said pilot chute being at the interior of said spiral.

13. A parachute pack assembly comprising a container having releasable closure flaps, means for releasably securing said flaps together, a canopy packed within said container, a pilot chute, a flexible pilot chute ejector, said pilot chute and ejector being rolled in convolutions, with said pilot chute enclosed in said ejector and packed within said container between said canopy and said flaps, and common manually operable means for releasing said flaps and withdrawing said pilot chute and said ejector from said container, said means for releasably securing said flaps together including a rip cord and said common means including a rip cord housing in which said rip cord is located.

14. A parachute pack assembly comprising a container having releasable closure flaps, means for releasably securing said flaps together, a canopy packed within said container, a pilot chute, a flexible pilot chute ejector, said pilot chute and ejector being rolled in convolutions, with said pilot chute enclosed in said ejector and packed within said container between said canopy and said flaps, and common manually operable means

for releasing said flaps and withdrawing said pilot chute and said ejector from said container, said means for releasably securing said flaps together including a rip cord and said common means including a rip cord housing in which said rip cord is located, said rip cord having movement within and relative to said housing and having movement with said housing whereby said flaps may be released by a pull on the rip cord and said ejector may be withdrawn from the container by a continuation of the pull on the rip cord.

15. A parachute pack assembly comprising a container having releasable flaps, means for releasably securing said flaps together, a canopy packed within said container, a pilot chute, a pilot chute ejector, said pilot chute and ejector being folded together and packed within said container between said canopy and said flaps, common manually operable means for releasing said flaps and withdrawing said pilot chute and said ejector from said container, said means for releasably securing said flaps together including a rip cord and said common means including a rip cord housing in which said rip cord is located, said rip cord having movement within and relative to said housing and having movement with said housing whereby said flaps may be released by a pull on the rip cord and said ejector may be withdrawn from the container by a continuation of the pull on the rip cord, and cooperating abutments on said rip cord and said housing to effectuate said last mentioned movement.

16. A parachute pack assembly comprising a container having a releasable portion to permit the release of a canopy, a parachute canopy packed within said container, a pilot chute attached to the peak of said canopy, a flexible ejec-

tor flap, said flap and pilot chute being rolled in convolutions, with said pilot chute enclosed in said ejector and packed in said container adjacent its said releasable portion, and means located externally of said container for withdrawing said ejector and pilot chute from said container and for freeing said pilot chute from said ejector.

17. A parachute pack assembly comprising a container having a releasable portion to permit the release of a canopy, a parachute canopy packed within said container, a pilot chute attached to the peak of said canopy, a flexible ejector flap, said flap and said pilot chute being rolled in convolutions, with said pilot chute enclosed in said ejector and packed in said container adjacent said releasable portion, and means located externally of said pack for releasing said releasable portion of said pack and for withdrawing said ejector and pilot chute from said container and freeing said pilot chute from said ejector.
